UNITED STATES PATENT OFFICE.

CHARLES W. ENGLEMIER, OF NEWARK, NEW JERSEY, ASSIGNOR OF ONE-HALF TO ADOLPH E. FINK, OF NEWARK, NEW JERSEY.

STAIR-TREAD.

No. 811,834.

Specification of Letters Patent.

Patented Feb. 6, 1906.

Application filed June 14, 1905. Serial No. 265,118.

To all whom it may concern:

Be it known that I, CHARLES W. ENGLEMIER, a citizen of the United States, and a resident of Newark, in the county of Essex and State of New Jersey, have invented certain new and useful Improvements in Stair-Treads, of which the following is a specification.

My invention relates to stair-treads.

It has for its object to provide a plate adapted to be placed over and engage a piece of carpet on a stair-step and be secured to said step so as to hold the carpet in place thereon, whereby a soft attractive protecting tread is provided for stair-steps.

It has for a further object to provide a stair-tread embodying advantages in point of simplicity and expensiveness of construction, durability, and general utility.

In the drawings, Figure 1 is a bottom plan view of the plate, partly broken away. Fig. 2 is a longitudinal vertical sectional view of the plate, showing it in position on a stair-step and securing a piece of carpet thereon. Fig. 3 is a longitudinal vertical sectional view of the plate.

In all the figures of the drawings illustrating my invention like reference characters designate corresponding parts.

Referring to the drawings, the stair-tread comprises a plate having a horizontal portion 1, provided with a downwardly and inwardly extending front portion 2. A hole 3 is provided in the horizontal and front portions, the edges of the horizontal portion bordering the opening being provided with downwardly-extending prongs 4, and the edge of the front portion bordering the opening being provided with laterally-extending prongs 5. A recess 6 in the under side of the plate borders the opening therein, and holes 7 in the horizontal portion and 8 in the front portion provide means for fastening the plate to the step.

To hold a piece of carpet on a stair by means of my plate, I press the carpet into the recess 6 so that the prongs pass into it, place the plate on a step and drive it back so that the front portion engages under the front edge of the step and the prongs 5 pass entirely into the carpet, then force the plate down so that the prongs 4 pass entirely into it, and finally secure the plate to the step by

means of screws 9, passed through the holes 7 and 8 therein into the steps. 55

It will be seen from Fig. 1 of the drawings, that when the plate is attached in the manner described the carpet will project through the hole therein beyond its outer surface and will be securely held. 60

I do not wish to be understood as limiting myself to the precise details and arrangements of parts shown and described, but reserve the right to all modifications within the scope of my invention. 65

Having now described my invention, what I claim as new, and desire to secure by Letters Patent, is—

1. A stair-tread comprising a plate provided with a top portion and a front downwardly-extending portion, said portions having an opening, downwardly-extending prongs on the edges of the plate bordering the part of the opening in the top portion and laterally-extending prongs on the edges bordering the part of the opening in the front portion, substantially as described. 70

2. A stair-tread comprising a plate provided with a top portion and a front downwardly-extending portion, said portions having an opening, prongs on the edges of the plate bordering the opening in the top portion and front portion, substantially as described. 80

3. A stair-tread comprising a plate provided with a top portion and a front downwardly and inwardly extending portion, said portions having an opening, prongs on the edges of the plate bordering the opening in the top portion and front portion, substantially as described. 85

4. A stair-tread comprising a plate provided with a top portion and a front downwardly-extending portion, said portions having an opening and a groove in their under face bordering said opening and prongs on the edges of the plate bordering the opening in the top portion and front portion, substantially as described. 95

5. A stair-tread comprising a plate provided with a top portion and a front downwardly and inwardly extending portion said portion having an opening, downwardly-extending prongs on the edges of the plate bordering the part of the opening in the top portion and laterally-extending prongs on the 100

105

edge of the plate bordering the part of the opening in the front portion, substantially as described.

6. A stair-tread comprising a plate provided with a top portion and a front downwardly and inwardly extending portion, said portions having an opening and a groove in their under face bordering said opening, downwardly-extending prongs on the edges 5 of the plate bordering the part of the opening in the top portion and laterally-extending

prongs on the edges of the plate bordering the part of the opening in the front portion, substantially as described.

Signed at New York, in the county of New York and State of New York, this 9th day of May, A. D. 1905.

CHARLES W. ENGLEMIER.
